PACKING RETAINER

Application filed June 21, 1928. Serial No. 287,062.

This invention relates to railway rolling stock and particularly to a retainer for packing of the journal boxes of the journals of railroad cars.

Such journals, as is well known, are supported by inverted bearing sections, mounted in the boxes, the latter being stuffed with packing, usually cotton waste, which is placed about the portion of the journal below the bearing and of course is prevented from actually leaving the box by the front cover of the same. There is considerable space, however, between the cover and the outer end of the journal and it frequently occurs that the packing loosens up and works away from the journal and into said space where it ceases to function to efficiently lubricate the journal and bearing. As a consequence the latter overheats and a "hot box" results.

The principal object of my invention is to avoid the occurrence of such "hot boxes" by preventing the packing from thus moving away from its properly packed relation about the journal by providing a retaining member which is placed in the box and which is so constructed as to efficiently hold the packing in its proper place.

At the same time the retainer is easily removed whenever necessary to withdraw old packing and replace the same with new. Also my retainer is of such a nature that it may be applied to standard journal boxes without necessitating any changes of any character being made to such boxes.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claim.

In the drawings similar characters of reference indicate corresponding parts in the several views:

Fig. 1 is a side section of a journal box showing my retainer in place therein.

Fig. 2 is a cross section of the journal boxes taken substantially on the line 2-2 of Fig. 1.

Fig. 3 is a perspective view of the retainer detached.

Referring now more particularly to the characters of reference on the drawings, the journal structure comprises the box 1, in the upper portion of which is mounted the inverted bearing member 2 against which the journal 3 bears; the sides of the bearing and journal being spaced some distance from the sides of the box. The front of the box as usual curves upwardly in front a certain distance as shown at 4 to the lower edge of the covering opening 5. These parts are all standard and I do not change the same in the slightest degree. The packing 6 is disposed about the lower portion of the journal and extends upwardly in the space between the journal and the sides of the box to a point substantially horizontally aligned with the axis of the journal, and also substantially fills the lower portion of the space in the box in front of the journal and below the cover opening.

My improved packing retainer comprises a single piece of spring steel rod. This rod is bent to form a pair of parallel arms 7, spaced apart a distance sufficient to fit between the journal and the sides of the box, and formed with vertically disposed spring loops 8 intermediate their ends. At one end 75 these arms are connected by a cross portion 9 which centrally of its extent is formed with a substantially horizontal and forwardly projecting loop 10. At their other ends the arms 7 are provided with upstanding prongs 11 80 disposed at an angle of approximately 90° to the arms. The dimensions of the retainer are such that when in position, the loop 10 bears against the upper surface of the lower forward portion of the packing and abuts 85 against the front surface 4 of the box below the cover opening; while the cross member 9 extends across and rests on such portion of the packing between the journal and the front of the box. The arms 7 slope upwardly relative to the journal and for a portion of their length bear against the top surface of the packing in the side surfaces of the box.

At the same time the tips of the prongs 90 then bear against the roof of the box as shown 100

in Fig. 1. When inserting the retainer through the opening 5, the lower or forward loop 10 is inserted first so that it extends down and ahead of the remainder of the retainer as indicated in dotted lines in Fig. 1. The retainer is then swiveled backward into position and pressed against the packing until the prongs bite against the roof. When in this position the pressure of the packing 10 prevents outward movement of the prongs from their engaged position with the roof, and said retainer prevents displacement of the packing from its proper compressed condition about the journal. The spring loops 15 8 permit the arms to yield when the prongs are engaged with the top of the box and thus permit the arms to be still further depressed intermediate their ends without disturbing the position of the prongs. These loops also 20 provide a greater area of surface to engage the packing than the bare rods would provide. When it is desired to remove the retainer, it is only necessary to pull the prong portions 11 both downwardly and outwardly, until they pass through the cover opening. 25 The entire retainer can then obviously be drawn clear of the box.

From the foregoing description it will be readily seen that I have produced such a device as substantially fulfills the objects of 30 the invention as set forth herein.

While this specification sets forth in detail the present and preferred construction of the device, still in practice such deviations from 35 such detail may be resorted to as do not form a departure from the spirit of the invention, as defined by the appended claim.

Having thus described my invention what I claim as new and useful and desire to secure by Letters Patent is:

A packing retainer for a journal box, said box having a bearing member against which the upper portion of the journal bears, said journal and bearing being spaced from the 40 side walls of the box, and packing partially filling the box from the front thereof and extending into the space between the journal and box; said retainer comprising side arms to extend upwardly and inwardly of said 45 space and adapted to bear against the upper forward surface of the packing therein, extensions on the inner ends of said arms projecting upwardly thereof to engage the roof of the box in said space, and a horizontal 50 member connecting the opposite ends of the arms to bear against the packing in front of the journal and to engage the front wall of the box.

In testimony whereof I affix my signature.
LYMAN P. MOORE.
